Alfie.

UNITED STATES PATENT OFFICE.

CHARLES P. STANBON, OF LYNN, MASSACHUSETTS.

VEHICLE SPRING.

1,418,031.

Specification of Letters Patent. Patented May 30, 1922.

Application filed April 30, 1919. Serial No. 293,799.

To all whom it may concern:

Be it known that I, CHARLES P. STANBON, a citizen of the United States, and a resident of Lynn, county of Essex, and Commonwealth of Massachusetts, have invented an Improvement in Vehicle Springs, of which the following description, in connection with the accompanying drawings, is a specification, like characters on the drawings representing like parts.

This invention relates to vehicle springs and has for its object to provide a novel form of spring particularly adapted for use on automobiles or any fast moving vehicles.

In the drawings of the embodiment of my invention illustrated and described herein;

Fig. 1, is a side elevation of my novel spring;

Fig. 2, a plan of the same;

Fig. 3, an end elevation on an enlarged scale; and

Fig. 4, a detail partly in section, on the line 4—4, Fig. 2, also on an enlarged scale.

The type of spring illustrated in Fig. 1, is commonly known as the full elliptic, that is, it comprises two concave convex halves, or sets of leaves, of similar construction, oppositely positioned and secured at their ends, as distinguished from the semi or half elliptic type, that is, either the upper or lower half; and also as distinguished from the three quarter elliptic type comprising one entire half and a shortened opposite half.

My invention is equally applicable to either type, and it will be apparent that the description of my invention as embodied in one half spring or one set of leaves will apply to all types mentioned.

My improved construction, Figs. 1, 2, 4, 40 comprises a master leaf 1, of full length, to each end 2, of which is suitably curved to embrace the bolt or spindle 3, Fig. 3, and lock the leaf thereto.

This end 2 is toothed at 4, Fig. 3, to engage similar teeth on the corresponding master leaf member 5 of the lower half, thus permitting each member to have a good locking grip on the spindle 3 and at the same time to yield slightly relative to the opposite member when the strains and stresses imposed on it by the weight and movement of the vehicle make it desirable.

Superimposed upon the leaf 1 are a plurality of shorter leaves 6, 7, 8, 9, 10, 11, 12, 55 13, each progressively shorter than the preceding one, and each provided near its end

and on each side at its lower edge with a depending lip 14, which engages the upper edges of the next lower leaf to prevent lateral movement of one relative to the other. 60

When a vehicle runs over a hump in the road, it is well known that, as the body of the vehicle goes up into the air the several leaves of each spring separate in proportion to the resistance encountered. 65

To prevent the leaves from separating too far with the danger that, when the body descends it will break the spring, it has been customary to restrain the separating movement of the leaves within certain limits by 70 means of clips secured to the under face of the inner leaf and embracing two or more of the leaves above it.

In order to use these clips it has been necessary to use full convex springs, that is, 75 convex throughout their length as distinguished from a convex-concave spring such as shown in Fig. 1, in order to avoid the danger of the clips on the lower half striking the clips on the upper half of the spring 80 when the spring is under pressure or compressed.

Or if the clips should not strike, and the inner leaf 1 of the upper half should be compressed until it rested upon a clip on the inner leaf 5 of the lower half, the upper leaf would undoubtedly break because the strain would be unequally concentrated on that particular point as a fulcrum instead of at the end of the spring. 90

While a convex-concave spring such as shown in Fig. 1, is much more flexible and yielding than a full convex spring it has been impossible to use it for anything more than the very lightest work because there 95 is not sufficient clearance between the upper and lower sets of leaves to use the clips for locking the leaves of each set together.

In order to permit the use of this most flexible form of spring, convex-concave, I 100 have conceived the novel idea of providing an unlocked or movable anchored master leaf 15 of such length that it may overlie the shortest leaf in the set and of movably anchoring it in such manner that it will permit a reasonable play of the several leaves beneath it, but restrain them against undue play or undue vertical separation.

To that end the leaf 15 in each case is shown as extended so that its ends underlie 110 and are movably anchored to the pins 16, and are upturned at 17 to limit the upward

movement of it and prevent the leaf from springing upward too far and away from the others, when released from tension, or when going over a hump.

5. The upturned ends 17 are separated slightly from the ends 2 of the leaf 1 to provide for the necessary endwise play thereof.

It will be obvious that by this construction the full advantage of the greater flexibility of the convex-concave spring can be obtained without the danger of breaking it under the conditions named. It will be noted that the master leaves 1, 5, of the spring are very flexible and almost touch in normal position.

When the weight is imposed upon the spring the long master leaves 1, 5, flex to substantially the dotted line position Fig. 1, and almost or quite meet, and in some cases with a smooth bearing one upon the other from the bolts 3 inwardly, and which would not be the case if clips were used. The free length of the leaves and therefore the working or flexing length obviously diminishes as they close up and meet under pressure, thus reducing very materially the danger of breakage, by transferring the load progressively to an increasing number of leaves.

20. Obviously my invention is not limited in all details to the foregoing described and illustrated embodiment, and I claim:

1. A full elliptic spring comprising a plurality of master leaves movably anchored 35 to oppositely positioned spindles, and op-

posed longer leaves individually immovably anchored to a common third spindle.

2. A full elliptic clipless spring comprising master leaves movably anchored, and opposite longer master leaves individually immovably anchored and interlocked at their ends to a common third spindle.

3. A full elliptic spring comprising master leaves movably anchored, opposed longer master leaves each relatively immovably anchored and a triangular anchorage for the leaves but jointly movable.

4. A full elliptic spring comprising master leaves movably anchored, opposed longer master leaves each relatively immovably but jointly movably anchored, and between the former master leaves to a joint anchorage.

5. A full elliptic spring comprising an anchorage, master leaves movably anchored thereto, and master leaves individually relatively immovably but jointly movable anchored thereto in different planes and interlocked one with the other upon a separate spindle.

6. An elliptic spring comprising inner and outer master leaves, leaves of varying length between them with leaf positioning ears thereon, the outer master leaves movably locked to one common set of anchorages, the inner master leaves individually immovably locked to a different set of anchorages and interlocked with each other.

In testimony whereof, I have signed my name to this specification.

CHARLES P. STANBON.
